UNITED STATES PATENT OFFICE.

CHARLES E. DE LONG, OF HOT SPRINGS, ARKANSAS.

SINGLE-TRIGGER MECHANISM FOR DOUBLE GUNS.

SPECIFICATION forming part of Letters Patent No. 699,291, dated May 6, 1902.

Application filed November 9, 1901. Serial No. 81,673. (No model.)

To all whom it may concern:

Be it known that I, CHARLES E. DE LONG, a citizen of the United States, residing at the city of Hot Springs, county of Garland, State of Arkansas, have invented a certain new and useful Improvement in Single-Trigger Mechanism, of which the following is a full, clear, and exact description, reference being had to the accompanying drawings, which form a part of this specification.

This invention relates to single-trigger lock mechanisms for double-barrel guns; and it has for its object to provide means for limiting the movements of the trigger as it is manipulated for firing the gun and to improve the means for preventing the unintentional firing of the second barrel by reason of the involuntary pull upon the trigger which takes place immediately upon the firing of the first barrel.

I have illustrated an embodiment of my invention by the accompanying drawings, in which—

Figure 1 is a side view of the lock mechanism, showing the parts in the position they assume when the gun is cocked. Fig. 2 is a similar view showing the position of the parts after the first barrel has been fired. Fig. 3 shows the parts in position for firing the second barrel, and Fig. 4 illustrates the same parts after the firing of the second barrel. Fig. 5 is a plan view of the parts shown in the other views. Fig. 6 is a section on the line 6-6 of Fig. 5.

The gun-lock mechanism illustrated in the drawings is in its main features of a well-known construction, and such parts as are common need not be described in detail.

Referring to the drawings, A indicates the frame; B, the barrels; E E, the sears, and G the trigger, which is provided with a plate G', secured to its heel or rear portion and which will be described in detail hereinafter. These parts in the accompanying drawings are represented as comprising parts of a double-barrel hammerless breakdown sporting gun. Some of the parts usually present in the lock of such a gun—as, for instance, the safety device—are not shown, as they form no part of my present invention and the omission

tends to clearness of illustration of those parts in which my invention is embodied.

The trigger is preferably situated between the two sears, and in an aperture in the plate G' thereof there is mounted a shiftable sear-contact Z, provided with a finger-piece z, projecting through the frame in convenient position for manipulation. Accordingly as the finger-piece is moved the contact Z will lie under the right or the left hand sear, so that upon the first pull of the trigger that barrel will be fired whose sear is raised. In order to fire the other barrel, I make use of what I term a "stepping sear-controller"—that is, a device which at different stages in the manipulation of the mechanism occupies different steps or positions, the last step or position being such as will cause a firing of the second barrel upon the trigger being pulled. N indicates this stepping sear-controller, and O a spring which engages therewith and tends to move it forward. It rests upon two lugs or posts secured to the frame A, its forward end upon the lug a' and its rear portion upon the lug a''. The rear under portion of the sear-controller N is shaped to form two steps or shoulders n n', and the forward of these, n, is adapted to engage with the rear upper edge of the lug a' and so retain the sear-controller in a retracted position.

The plate G' of the trigger is provided with a heel or projection g, which is arranged to engage with the sear-controller and raise it as the trigger is pulled. This heel portion of the trigger is preferably situated a little back of the lug a', and its upper edge lies a little below the upper edge of the lug when the trigger is in its lowermost or forward position.

The stepping sear-controller is provided with a pair of hooks or catches y, disposed one on each side of the sear-controller and arranged to engage with the sears E when the controller is moved forward, but to be free therefrom at other times.

The trigger-plate G' is provided with pins or projections x, arranged to lie under the ends of the hooks when the sear-controller is moved forward, so that the raising of the trigger-plate will positively and directly move the hooks and through them the sears.

The forward end of the sear-controller is so disposed that it will be engaged and moved backward by some part of the gun which is moved when the gun is broken for the purpose of loading—as, for instance, the bolt R. When it is thus moved back, the shoulder or step n engages the edge of the lug a^4 and holds the sear-controller in its rearmost position. If now the trigger be pulled, the barrel under whose sear the contact-piece Z may be situated will be fired, and at the same time the rear portion of the sear-controller will be lifted from engagement with the lug and will be moved forward a short distance by the spring O into the position indicated in Fig. 2, with the step n' engaging with the rear upper edge of the heel g of the trigger and with the shoulder n above the top of the lug a^4 . If now the pressure upon the trigger be released and it move downward under the influence of the trigger-spring, the parts will assume the position shown in Fig. 3, the heel of the trigger having disengaged the step n' and the sear-controller having been moved forward by its spring O into position to fire the second barrel. This will carry the hooks y under the sears, so that the next pull of the trigger will, through the sear-controller, the hook, and the sear of the unfired barrel, result in a firing of the second barrel.

In order to prevent the unintentional firing of the second barrel by the involuntary pull upon the trigger, I combine with the sear-controller a retarding device similar to that shown in my Patent No. 690,243, dated December 31, 1901.

n^5 represents a pawl connected with the rear end of the sear-controller and arranged to engage with a ratchet-wheel p , mounted upon a shaft supported in the lug a . Upon this shaft is mounted a spur-wheel p' , which engages with a spur-pinion p'' . Upon the same shaft with the pinion p'' there is mounted an escapement-wheel p''' , with which there engages a vibrating escapement drag-pawl p^4 . A spring n^6 holds the pawl n^5 in engagement with the ratchet-wheel. The parts of this escapement mechanism are very light and capable of rapid operation; but they nevertheless operate to retard the forward movement of the sear-controller sufficiently to permit the involuntary pull to take place before the sear-controller arrives at such a forward position as to permit the firing of the second barrel. As this mechanism is fully described in my aforesaid application, its operation and functions need not be further described herein.

I have also invented a means for preventing an undue movement or draw of the trigger upon the firing of the first barrel and also for preventing the trigger from falling under the influence of the trigger-spring (which is not herein shown) after the firing of the first barrel and before the second barrel is fired.

W represents a lever pivoted to the frame

and arranged with its upper end in position to engage with the rear end or portion of the sear-controller. It is provided with a slot w , of peculiar construction, into which a pin V, carried by the trigger-plate, is adapted to enter. A spring U, having bearing against a stationary part of the mechanism, as the lug a , tends to swing the lever in a forward direction. When the gun is cocked and in position for firing, the parts occupy the position shown in Fig. 1, with the sear-controller locked in its rearmost position, the trigger down, and the lever W forced backward by reason of the engagement of the sear-controller with its upper end. When the parts are thus positioned, the pin V lies outside the slot w and just below the open end thereof. The pull of the trigger, which results in firing the first barrel, brings the parts to the position indicated in Fig. 2. The sear-controller by this pull of the trigger is forced upward, so that the shoulder or step n is released from the lug a^4 and the controller is by the spring O forced forward. The pin V, carried by the trigger-plate, is at the same time moved upward, and the spring U forces the lever W forward, the pin moving over the inclined face 2 at the entrance of the slot w . Before the pin fully enters the slot, however, its movement, and consequently the movement of the trigger, is arrested by the pin coming into engagement with the shoulder 3, situated at the entrance to the slot w at the upper edge thereof. This device prevents any overdraw of the trigger, allowing it to be moved just far enough to operate the sear and fire the first barrel. After the first barrel has been fired and as the trigger is released in order to fire the second barrel the lever W is forced still farther forward and comes to the position indicated in Fig. 3, where it rests upon a shoulder 4 at the lower end of the slot. The engagement of the pin with this shoulder operates to arrest the downward movement of the trigger, holding it in such position that but a short pull is required to fire the second barrel. The pull which results in firing the second barrel carries the pin into the upper portion of the slot, as indicated in Fig. 4.

When the gun is broken for discharging the shells and reloading, the sear-controller is moved backward, and it in turn moves backward the lever W, restoring the parts to the position shown in Fig. 1.

What I claim is—

1. In a single-trigger gun-lock mechanism the combination of a trigger, the sears, the sear-controller provided with means adapted to engage with the sears when moved forward, means for holding the sear-controller retracted, means which tend to force the sear-controller into a position to cause said controller to engage with the sears, and means carried by the trigger for moving one of the

sears and for tripping the sear-controller under the first pull of the trigger, substantially as set forth.

2. In a single-trigger gun-lock mechanism, 5 the combination of a trigger provided with a pin, a lever provided with a stop for limiting the pull of the trigger, and provided with a slot with which said pin engages, said lever having a second stop on the opposite side of

the entrance of the slot with which said pin is adapted to engage to limit the return of the trigger, and a spring for forcing the lever toward the pin, substantially as and for the purposes set forth.
